NICHOLAS JENKINS, OF NEW YORK, N. Y

Letters Patent No. 67,553, dated August 6, 1867.

IMPROVEMENT IN MACHINES FOR MAKING MOULDINGS

The Schedule referred to in these Letters Patent and making part of the same.

TO ALL WHOM IT MAY CONCERN:

Be it known that I, NICHOLAS JENKINS, of the city and county of New York, and State of New York, have invented certain new and useful Improvements in Machines for Panelling and Variety Moulding; and I do hereby declare that the following is a full and exact description thereof.

I will first describe what I consider the best means of carrying out my invention, and will afterwards designate the points which I believe to be new, reference being had to the two sheets of drawings, which represent the novel parts of my machine with so much of the other parts as is necessary to indicate their relations thereto.

Figure 1 is an end view of the machine.

Figure 2 is a front view of the main portion of the machine and a cross-section of the templet and of the wood which is being operated on.

Figure 3 is a central vertical section through the lower end of one of the cutting arbors.

Figure 4 is a horizontal section on the line S S in fig. 3, as seen from below.

Figure 5 is a central vertical section showing another form of the cutter and its connections.

Figure 6 is a plan view seen from below.

Figure 7 is a top view of one form of my templet.

Figures 7 A and 7 B represent cross-sections of the parts detached from each other.

Figure 8 is a top view of the wood after it has been panelled.

Figure 9 is a cross-section of the same; and

Figure 10 is a cross-section showing the piece which is fitted in the table to adapt the machine for variety moulding.

Similar letters of reference indicate like parts in all the figures.

A is the foundation or the main framework, and A¹ is the fixed portion of the head supported firmly thereon. B¹ B² are the arbors, mounted in carriages C¹ C² which are adapted to move vertically in dove-tailed channels as is usual in this class of machinery. The ordinary loose pulley above, with the driving-pulley and belt, the latter capable of being shifted from the loose pulley B³ on to the pulleys mounted on the upper extremity of the respective arbors, B¹ and B², are all of the ordinary construction, and are operated in the ordinary manner. D is a cross-traversing carriage adapted to slide horizontally in a head, w, which is adapted to move vertically in the head A¹, as represented. E is a movable table on which the work is operated in either direction horizontally by the aid of the cranks, as represented. The operator holds the two cranks, one in each hand, and by turning one or both simultaneously in one direction or the other, moves the carriage E in any direction desired, according as is required to produce the proper pattern. This portion of the operation is identical with that of many other approved forms of panelling and variety moulding machines. E¹ E² are clamps operated by the thumb-screws e¹ e², and adapted to press upon and firmly confine the templet and the wood which is to be operated upon. G is the main or exterior templet; G' is a templet adapted to fit accurately within the templet G. There may be still other templets fitting within the templet G', if preferred. The inner and working edges of these several templets may be alike in form and proportion, or may be very diverse, as preferred. But the thickness of the several templets is equal, or about equal, and the exterior of one corresponds with such accuracy as to fit immovably within the interior surface of the templet or portion of the templet which surrounds it.

In operating my machine the exterior templet G is applied first upon the wood H, and is firmly clamped by the clamps E¹ E². After the cutters have traversed quite around the interior of these templets, and produced a corresponding panelling cut in the wood H, the cutters are lifted and the next succeeding templet G' is dropped into place. The same or different cutters are now applied and traverse around the interior edge of the templet G'. c c are notches formed in the sides of the carriages C, and adapted to sustain the latter and their connections by a hook received therein. I, in figs. 1 and 2, is the main body of my hook; it is adapted to turn on the pivot i, and is acted on by the spring J tending to force it into contact with the carriage C. K is a movable hook-piece mounted in the main body I; it is traversed up and down in the latter by means of the thumb-screw L. By turning this latter in one direction or the other the hook-piece K is raised and lowered with the greatest accuracy, and adjusted as finely as may be required, while, by simply pulling the entire body I and its connections away from the carriage C, in opposition to the gentle force of the spring J, I am able to liberate the

carriage C, and to raise and lower it immediately so as to shift the hook into the next notch above or below, or to raise or lower it to any great extent desired. I have represented only one of my improved hooks. Both may be such in practice. M is a hand-lever turning on the pivot m , and connected to the sliding head D and C so as to raise and lower the latter with great facility. N is a lever, turning on the pivot n , and actuated by the coiled spring N' so as to hold its cutting edge in contact with the transverse sliding-head D. There are two notches in the latter which are adapted to receive this lever N, and hold the transverse-sliding head D stationary when one of the shafts or beveling-arbors B is exactly in line with the loose pulley which carries a belt above. This part of the mechanism is analogous to that in common use in this class of machines.

I will now describe the provision for raising and lowering the cutting parts simultaneously and adjusting them at different heights.

W is a vertically-traversing carriage; it is guided on upright ways A^2 formed on the fixed head A^1 . This carriage W carries the brackets which support the loose pulley, before described, and also supports the several working parts which are driven by the power derived from the belt. The dove-tailed horizontal grooves or ways provide for the lateral traverse of the carriage D. The lever N is pivoted upon this vertically-traversing carriage W. This mounting of so many of the working parts upon a single vertically-traversing carriage gives very important advantages which will be readily recognized by those familiar with this class of machinery. It carries the horizontal carriage D and all its several immediate connections, also the lever N, also the stout upright arm A^3 , which supports the loose pulley B^3 , several times above referred to, also the belt-shipper and the friction-spring and guides which hold it in the required positions. The means of adjusting this carriage W in the required positions up and down on the slides A^2 are partly indicated in the drawings, and the remainder will be readily understood. X is a hand-crank, which turns a shaft, x, which carries a small spur-wheel, indicated in dotted lines in fig. 2. This wheel meshes into a rack on the face of the upright A^1 , and by turning the hand-crank X the entire carriage W is moved up and down. In order to hold it in any required position, and yet allow it to be adjusted readily and rapidly without the necessity for liberating any ordinary pawls, set-screws, or the like, I provide the spring Y which is connected at each end to the carriage W, and presses its coils, near the centre of its length, against the notched wheel represented on the shaft X. This serves as a kind of spring-pawl by catching in the several recesses or notches in this wheel. It holds with sufficient force therein to support the weight of the parts, but not with so great force as to prevent the crank X from being readily turned in either direction when required.

I will now describe the peculiarity of the cutter-head and its connections. O is a brace, bolted upon the under side of one of the carriages C^1 or C^2 . Both may be alike. I will describe simply that which is attached to the carriage C^1 . The lower end of the arbor B^1 is threaded, as represented in fig. 3, and matches a female screw on the interior of the shell or head P. The cutters, carefully worked to the proper form to produce the panelling desired, are bolted upon the squared parts of this latter shell in the manner represented. Figs. 6 and 7 show an adaptation of the arbor B to receive the stem of the cutter internally. This construction may be used in connection with the one shown in fig. 3, and is, it will be perceived, so represented. Fig. 6 shows the same construction as is shown in fig. 3, but with the further adaptations now to be described. Q is a pin of cast steel adapted to fit into a corresponding socket bored in the lower end of the arbor, which we will continue to describe as B^1 . It is confined and released therein by the pinching-screw represented, and is adapted at its lower extremity to remove the wood to the desired pattern. V is a screwed thimble, having a projecting lip or flange adapted to form a shoulder as it is screwed up into a hole in the brace O, which is threaded to receive it. The lower extremity of this thimble V is slender, and encircles the pin Q without actually touching it so as to create any appreciable friction. This extension V^1 is turned perfectly round, and is polished nicely, and forms a surface against which the several templets, above described, may be successively traversed in panelling by the aid of my machine. It will be perceived that this thimble V rises and sinks with the cutter and is always in immediate proximity to the cutting portion. R, fig. 1, is a pin, which in its present position performs no function except that of being held and holding the ring T against being lost. Its use is to fit into the hole represented in dotted lines in the table E, and in the under table F, and in the main body A, so as to hold all these parts in a fixed position when desired for variety moulding.

My device for adapting the machine to produce variety mouldings is very simple and easily described. T is a ring of metal, carefully turned and polished. It fits nicely in the corresponding circular recess, indicated in dotted lines in the table E. This recess is so related to the holes which receive the pin R that it is exactly in line with the loose pulley B^3 when the table E is locked in position. In applying my wood for variety moulding I apply it upon the top of the templet, holding it by spurs thereon, as is common in some of the best machines of this class. On pressing the templet with the wood thereon against the ring T, and moving it around the cutters, reduce the wood to the corresponding form in the same manner as with other variety moulding machines, except that the work is performed by the same machine as performs the panelling above described, with this very slight modification. There may be two or more of these guides T, if desired.

Some of the advantages due to certain features of my invention may be enumerated as follows:

First, by reason of the fact that my adjustable hook I & K L is constructed with a capacity for delicate adjustment of the part K up and down and arranged to operate in connection with the notches in the sliding-carriage C, as represented, I am able to graduate the depth to which the cutters act with extreme nicety, while the carriage is secured and released with all the ease and rapidity possible with other and ordinary hooks.

Second, by reason of the fact that the guide V is round, and is mounted concentric to the arbor of the cutter, I am able to control the action of the cutter so as to traverse it along the edge of a templet without subjecting the guide or the templet to any friction due to the rotary motion.

Third, by reason of the fact that my ring T is adapted to be fitted at pleasure in the recess in the bed E,

and to be so held there exactly in line with the cutter above, I am able to manufacture variety mouldings with the same machine as is employed for panelling, and with very little trouble or expense in the changing of the machine from one condition to the other.

Fourth, by reason of the fact that the templets G fit over instead of under the wood H, and that the machine is provided with means for firmly holding both upon the table E, and for moving the latter in all directions, as required, I am able to execute large work with a small machine, and to guide the material with great certainty and ease.

Fifth, by reason of the fact that my templets G G', &c., are fitted accurately one within the other, as represented, I am able to execute a succession of operations upon the same piece of wood H, by dropping in the successive inside templets and changing the cutters, if necessary, by running the cross-head D across or otherwise without liberating and readjusting the wood or the original external templet; I am, therefore, able to secure a mathematical exactness of position without any labor or care.

Sixth, by reason of the fact that the single head *w* carries the entire cross-head D and the connected parts, so that it is capable of being raised and lowered with ease to any extent usually required without requiring any adjustment of other parts, I am able to operate on different thicknesses of wood properly and with equal effect without a moment's delay and without deranging any of the varied capacities and nice adjustments of the machine.

Having now fully described my invention, what I claim as new in panelling and variety moulding machines, and desire to secure by Letters Patent, is as follows:

1. I claim the adjustable hook I K L, arranged to operate in connection with a sliding carriage, C, and cutting arbors B¹ B², constructed and operating substantially in the manner and for the purpose above described.

2. I claim the round guide V, mounted concentric to the arbor of a cutter, supported above as described, and rising and sinking therewith without touching the cutter, so as to make any considerable friction against the same, substantially as and for the purpose herein set forth.

3. I claim the employment on a cutting-arbor supported above, as specified, of the stationary guide T, mounted below the cutter, and adapted to serve as a guide in variety moulding, substantially in the manner herein specified.

4. I claim fitting the templet upon the wood H and securing it thereon, in combination with means for moving both in every direction, the whole being arranged relatively to one or more cutters Q revolved above, substantially as and for the purpose herein set forth.

5. I claim, in a wood-working machine, confining and releasing the entire series of templets G G', by confining and releasing the outer one above, substantially as and for the purpose herein specified.

6. I claim the single head *w* alone, carrying the two or more carriages C¹ C², and cutting-arbors B¹ B², and their connections, provided with means for raising and lowering the whole together, substantially in the manner and for the purpose herein specified.

NICHOLAS JENKINS.
